(57) **CLAIM**

The ornamental design for a pivotable eyeglass frame, as shown and described.

DESCRIPTION

FIG. 1 illustrates a perspective view of a pivotable eyeglass frame, according to the present invention.

FIG. 2 illustrates a front elevational view of the pivotable eyeglass frame as shown in FIG. 1.

FIG. 3 illustrates a rear elevational view of the pivotable eyeglass frame as shown in FIG. 1.

FIG. 4 illustrates a right-side elevational view of the pivotable eyeglass frame as shown in FIG. 1.

FIG. 5 illustrates a left-side elevational view of the pivotable eyeglass frame as shown in FIG. 1.

FIG. 6 illustrates a top plan view of the pivotable eyeglass frame as shown in FIG. 1.

FIG. 7 illustrates a bottom plan view of the pivotable eyeglass frame as shown in FIG. 1.

FIG. 8 illustrates a right-side view of the pivotable eyeglass frame as shown in FIG. 1, when worn by a user in a lowered position; and,

FIG. 9 illustrates a right-side view of the pivotable eyeglass frame as shown in FIG. 1, when worn by a user in a raised position.

The broken lines in the drawings depict environmental structure and form no part of the claimed design.
